UNITED STATES PATENT OFFICE.

STEPHEN HIPKINS, JR., OF MARTIN'S FERRY, OHIO.

DESIGN FOR A TUMBLER OR OTHER GLASSWARE.

SPECIFICATION forming part of Design No. 18,650, dated October 2, 1888.

Application filed July 25, 1888. Serial No. 281,044. Term of patent 3½ years.

To all whom it may concern:

Be it known that I, STEPHEN HIPKINS, Jr., a citizen of the United States, residing at Martin's Ferry, in the county of Belmont and State 5 of Ohio, have invented certain new and useful Improvements in a Design for Pressed Glass-ware; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This design embraces a pattern which forms a background; also a second distinct pattern superimposed on the first pattern and forming a tie or binder, so to speak, for the ground pattern, the two patterns being raised, the one 20 being higher than the other. This design gives the appearance of a double pattern.

In its broad feature the design consists of ribs and checked strips between the ribs, the ribs and strips being oblique and the ribs arranged in groups.

25 In its specific formation the design consists of oblique ribs arranged in groups and having checked surfaces or strips between the groups of ribs and checked ribs or bars extending 30 over the ground formed by the oblique bars and checked surfaces, as will hereinafter be

more fully described and claimed, and shown in the accompanying drawings, in which—

Figure 1 is a side view of a tumbler embellished with my design; Fig. 2, a cross section 35 on the line X X of Fig. 1, and Fig. 3 a vertical section on the line Y Y of Fig. 1.

My design is adapted for all kinds of glass-ware, and particularly for articles of table-ware, and is shown applied to a tumbler, A. 40 The ground pattern, which is raised, is composed of the oblique ribs or bars B, arranged in groups, and the checked strips C between the groups of oblique bars B. The superimposed pattern composed of the checked ribs 45 or bars D is raised higher than the ground pattern, and presents the appearance of binding the oblique ribs B and the checked strips C together. The checked ribs D, formed from intersecting bars, embrace the entire ground 50 pattern.

Having thus described my invention, what I claim, and desire to secure by Letters Patent, is—

The design for a tumbler or other glassware, 55 substantially as herein shown and described.

In testimony whereof I affix my signature in presence of two witnesses.

STEPHEN HIPKINS, JR.
